GAME APPARATUS

William R. McDonald, Los Angeles, Calif.

Application February 1, 1932, Serial No. 590,117

6 Claims. (Cl. 273—122)

This invention has to do with games of skill and is more particularly related to apparatus for playing a game in which the final score obtained is dependent entirely upon the skill of the operator. Although it is one object of the present invention to produce an apparatus of the class described which is coin-operated, it is to be understood that the invention may be embodied in devices for home use in which the construction 5 will be somewhat modified and will of course be cheaper to manufacture.

The device contemplated by this invention consists in a general way of a table, a shelf, or a board which has a playing field formed thereon. The 10 playing field is provided with an uneven surface having a plurality of depressions and corresponding elevations formed thereon. In addition to the depressions and elevations I prefer to provide the playing field with an irregular winding path leading 15 from a starting point to a finishing point. This path is provided with a series of traps or hazards and the various depressions are provided with wells or pockets adapted to receive playing pieces, the wells being evaluated according to the 20 ease with which a playing piece may roll from the path into the corresponding depression. The well at the end of the path is preferably made the most difficult to approach and is, of course, given the highest value and the wells as they become 25 nearer the starting point are of correspondingly decreasing value.

The object of the game is to advance a playing piece or playing pieces by means of a suitable arm or cue from the starting point into the well 30 or wells of highest value. It is to be understood, of course, that the rules of play may be varied somewhat, for example, the various depressions instead of being provided with wells may simply be provided with rather a steep inclined edge so as 35 to make the approach from the depression to the path difficult and the object of the game may be to advance the playing piece along the path into a well or cup provided at the end of the path with the minimum number of "strokes" to advance the 40 playing piece leaving the path at the various hazards. In this event the score would be calculated by the number of trials necessary to place the ball on to the path after it has been lost in the hazards, similar to golf.

I consider it a feature of the present invention to provide an arm for moving the playing piece which is operated through a compound lever so that it has universal movement over the field of play. This arm is preferably arranged so that 45 the longitudinal portion of the arm is positioned

a substantial distance above the field of play so as to clear the playing pieces, the end of the arm being provided with a downwardly projecting nose or knob which is used to advance the ball or playing piece along the path. In this particular form of my invention the field of play is provided with a plurality of cups or wells, each of which is constructed so as to contain a single playing piece. The playing pieces, after they have been received in the cup or well, cannot be removed until a 5 release to be described later in the specification, has been effected by means of the coin control. In addition to the coin operated means for releasing the balls or playing pieces from the various pockets or wells, I provide additional means 10 for delivering the playing pieces individually to the field of play. It is to be understood that, in operating the device as a coin operated machine, one or any desired number of playing pieces, for example four, will be placed in the apparatus and 15 means are provided for individually delivering all four of these pieces to the field of play, following one operation of the coin control.

The whole apparatus is enclosed within a case, and the handle for operating the arm, a handle 20 for delivering the balls to the field, and a plunger or handle for operating the ball release are preferably all extended from one side of the case.

As an added feature to the game contemplated by this invention, I have devised means in the 25 form of a mirror for reflecting the field of play to the operator, such means being associated with additional means for concealing the actual field of play from the view of the operator. The reflecting means are preferably optional in their 30 use, but it will be seen that such means, in addition to the peculiar construction of the arm and arm operating mechanism, makes the movement of the arm with respect to the handle quite 35 confusing and will tax to a greater degree the skill 40 of the operator.

The details in the construction of a preferred form of my invention, together with other objects attending its production, will be best understood 45 from the following description of the accompanying drawings which are chosen for illustrative purposes only, and in which

Fig. 1 is a perspective view showing a preferred form of my invention;

Fig. 2 is a plan view with parts broken away 50 illustrating the operating mechanism of the device shown in Fig. 1;

Fig. 3 is a sectional elevation which may be considered as having been taken in a plane represented by the line 3—3 in Fig. 2;

Fig. 4 is a sectional elevation taken in a plane represented by the line 4—4 in Fig. 2;

Fig. 5 is a sectional elevation taken in a plane represented by the line 5—5 in Fig. 4;

5 Fig. 6 is a fragmentary section enlarged to illustrate the mechanism employed in delivering the balls or playing pieces to the field of play;

10 Fig. 7 is a fragmentary section taken in a plane represented by the line 7—7 in Fig. 2 and enlarged to illustrate further details in the ball elevating mechanism;

15 Fig. 8 is a sectional view taken in a plane represented by the line 8—8 in Fig. 2 and illustrates certain details in the construction of the coin control;

Fig. 9 is a fragmentary view of the element shown in Fig. 8 illustrating the manner in which a coin operates the coin controlled mechanism;

20 Fig. 10 is a fragmentary section taken in a plane represented by the line 10—10 in Fig. 8;

Fig. 11 is a fragmentary section taken in a plane represented by the line 11—11 in Fig. 9;

25 Fig. 12 is a fragmentary sectional elevation taken in a plane represented by the line 12—12 in Fig. 2;

30 Fig. 13 is an enlarged sectional elevation taken through the shelf or table comprising the field of play and illustrating the manner in which the path and irregularities of the field are formed thereon; and

Fig. 14 is a fragmentary view showing a modified form of my invention.

More particularly describing the invention as herein illustrated, reference numeral 11 indicates 35 a box or case which is shown as having a bottom 12, a top 13 and side members generally indicated by reference numeral 14. The bottom 12 is preferably hinged to the lower portion of the case 11, so as to permit access into the coin receiving 40 box and is provided with a lock indicated by reference numeral 15. The top 13 is also hinged to the central portion of the box and is locked thereto by the lock generally indicated by reference numeral 16. It is to be understood that 45 this is merely a preferred form of construction, other expedients in the box construction will of course be readily apparent to those familiar with the art and where the game is made for home use rather than commercial use, this construction 50 may of course be varied considerably. The top 13 of the box is provided with an opening 17 which contains a transparent window 18 through which the field of play to be described later in the specification may be observed.

55 As pointed out earlier in the specification the apparatus may be provided with a mirror 19 which is shown as being hinged to the cover near the forward edge of the opening 17 so as to reflect the field of play to the observer. In addition I provide a shield 20 which is mounted near the rear edge of the opening so as to conceal the actual field of play from the observer. Inasmuch 60 as the mirror reverses the position of all objects on the field of play, it will be seen that this is more or less confusing and is a greater tax on the skill of the player. Mounted in the case 11 below the window 18 I provide what I may term a shelf, table, or playing board 22 which has formed upon its upper surface a field of play 23. This 65 field of play is provided with an irregular surface having a plurality of depressions indicated generally by reference numeral 24 and a plurality of elevations indicated generally by reference numeral 25. Each depression is shown as being 70 provided with a well or cup indicated by refer-

ence numeral 27. In addition to the depressions 24 the field of play is provided with an irregular winding path indicated by reference numeral 28 which follows a more or less crooked course along the upper edge of the various elevations and twists in and out among the depressions containing the wells. This path is made extremely shallow 5 so that a playing piece such as the ball or sphere 29 when carefully moved therealong will not roll into the depressions on either side of the path. The path is, however, provided with traps or hazards, generally indicated by reference numeral 30 in Figs. 2 and 13. These hazards are in the form of depressions in the path which are associated with grooves or channels having a very slight slope into which the playing piece if not 10 carefully guarded by the advancing means will roll into a well of low value.

It is an important feature of the apparatus that the depressions into which the playing piece or 20 ball will most readily roll have the lowest value, for example the well nearest the starting point has a value of 10, the well in the center of the field of play toward which all of the inside depressions lead also has a value of 10, and so on until the 25 well at the end of the path which is the most difficultly accessible, has a value of 500. The 500 well is placed upon a slightly raised portion from which the playing piece has a tendency to roll into either of the 10 value wells and it requires 30 the utmost skill and care to advance the ball or playing piece into this well. It is to be understood, of course, that the arrangement of the wells or pockets and the manner of evaluating them may be varied without departing from the scope 35 of the invention.

In addition to the wells just described on the main field of play, I have provided a series of wells along the edge of the field of play which may for example, have a value of 5 or a minus 5, 40 depending upon whether or not means are provided for retaining the playing pieces in these wells. Instead of using the irregularly surfaced field with the depressions therein, I may obtain the same effect by using playing pieces of steel 45 or other magnetic material and placing magnets in or below the field of play in offset relation with the path as indicated at M in Fig. 14, where the field of play is indicated at E. The magnets may also be used with the irregular field.

It is to be understood that the field of play need not necessarily be a miniature field such as shown in the drawings, but may be of dimensions corresponding substantially to the ordinary pool or billiard table, in which event the wells instead of 55 being in the form of cups provided in the various depressions, may if desired be constructed as hazards so that the ball or playing piece can be advanced with difficulty from the well back up onto the shallow path. In this event the object 60 of the game would not be to obtain the largest score possible, which is computed by adding the value of the various wells into which the balls or playing pieces lodge themselves, but would be calculated by the minimum number of strokes or 65 movements of the arm or cue employed in elevating the ball or playing piece from the various hazard wells back on to the path, in advancing the ball to the end of the path.

In the device chosen for purposes of illustration 70 and which forms the subject matter of the present application, however, the wells on the field are made in the form of cups which are of a size such that they will be filled by one of the balls or playing pieces 29 and which are formed by 75

boring holes of the proper diameter completely through the board or table which comprises the field of play. The balls or playing pieces are held in the pockets by a coin-released mechanism 35 5 to be described later in the specification.

As was mentioned in the early part of the specification, various means may be employed in advancing the ball or playing piece from its starting point A along the path, for example, 10 if the field is of a large size and designed for home use, an ordinary billiard cue may be employed for this purpose. In the present device I show the ball advancing means as comprising an arm 38 which is mounted on the case above the 15 playing field at a distance such that the longitudinal portion of the arm will clear a ball or playing piece on the field. The end of the arm is projected downwardly to form a knob or nose 39 which is preferably enlarged and is arranged 20 so as to be moved into engagement with the ball or sphere on the field of play. The arm 38 may be operated through a slot at one edge of the field of play by a handle formed directly thereon but as a means of adding interest to the game and 25 increasing the element of skill therein I provide this arm with a novel operating mechanism which is shown as comprising a lever member 40 which is pivoted to the arm as indicated at 40a and which is swingably and slidably mounted in the 30 case by passing it through an opening 41 in a head 42 formed on a shank 43 which is rotatably mounted in a standard 44 secured to a shelf or horizontal partition 45 in the case by means of bolts 46. The lever 40 is provided with an adjustable stop 48 which limits its outward movement and the outer end of the lever is provided 35 with a handle 49. It will be seen, therefore, that the lever 40 has both a sliding and swinging movement in the case and that this lever will act 40 in combination with what I have termed a fulcrum lever 50 to impart universal movement to the arm 38 in a substantially horizontal plane or in a plane which is parallel with the field of play. The fulcrum lever 50 is pivoted to a bracket member 38' which forms a part of the lever 38 and has its fixed pivot on a standard 51 which is secured to the plate 45, as indicated at 52.

In order that the arm may always be yieldably drawn toward a neutral position I provide 50 a tension spring 54 which is shown as having one end secured to the pivot pin 40a and is secured at its other end to the side of the case as indicated at 55. In the operation of the device it will be seen that by skillfully sliding and swinging 55 the lever 49 a ball or playing piece 29 may be advanced along the shallow path on the field of play and the knob or nose 39 may be skillfully used to prevent the ball leaving the path in the various traps or hazards. The dotted line position of the lever and arm mechanism in Fig. 2 60 indicates the manner in which the knob of the arm is engaged with a playing piece during its advance along the path.

In a coin-operated game of this nature, as 65 pointed out above, I prefer to use several balls or playing pieces which may be advanced into the various pockets, such playing pieces being retained in the pockets by a sliding gate plate 60 which is shown as being mounted on the end 70 portion of a plunger member 61. The plunger 61 is supported by a guide bracket 62 secured in any suitable manner in the case and extends through an aperture 63 in a partition member 64 and through an aperture 65 in the side of the 75 case so that its end may be engaged by an op-

erator for moving the plate 60. The plate 60 is provided with a plurality of apertures 66 arranged so as to be brought into alignment with the various pockets when the plunger is advanced to its forward or inner position. A tension spring 67 is provided for the purpose of maintaining the plate in the position shown in Fig. 3 where the apertures or pockets are closed. 5

The movement of the plunger 61 is governed by a coin operated mechanism which is shown 10 as comprising a lever member 68 pivotally mounted upon a bracket 69 as indicated at 70. The end 71 of this lever member is positioned below the mouth 72 of a coin channel 73 and this coin channel 73 is positioned with its open 15 upper end beneath a coin slot 74 formed in the top 13 of the case. The end 71 of the lever member is positioned above an opening 75 in the shelf or partition 45 through which the coin is adapted to fall into a coin compartment 76 there- 20 below. One side of the coin channel is provided with an opening 78 adapted to receive the bent end portion 79 of a rod member 80 which has its upper end secured in a block 81 mounted on the plunger 61. This block is situated so as to 25 constitute a stop which will normally engage the upper end of the lever member 68 which normally rests upon the plunger 61. However, when a coin is dropped into the coin channel it falls upon the end portion 71 of the lever lifting it to 30 the position indicated in the dot and dash lines in Fig. 4, so that the block or other suitable stop 35 in Fig. 4, so that the plunger will pass beneath the lower end of the lever, permitting the plunger to be moved inwardly to a position in which the balls will fall through the openings in the field of play. The inward movement of the plunger during such an operation forces the bent end 79 of the rod 40 80 into engagement with the coin C, pushing it across the end 71 of the lever member and into 45 engagement with a gate 82 which is hinged to the opposite side of the coin channel, as indicated at 83. As the plunger is moved to a position at which the balls or playing pieces are released 50 the coin is pushed clear of the lever member so that it falls through the opening 75 into the receptacle 76. The lever member is then free to drop by gravity back into its normal position where it rests upon the plunger when the plunger is released and drawn back to its position by the 55 coil spring. The plunger cannot again be operated until another coin is deposited into the coin channel. 60

After the balls or playing pieces have been released in the manner just described, they drop 55 onto an inclined plate or floor 90 which is situated just below the field of play and which inclines downwardly to an inclined groove 91 which slopes toward an opening 92 formed in the vertical partition 64. 65

For the purpose of delivering the balls or playing pieces to the field of play, I provide an arm or lever member 93 which is pivoted to the partition 64 as indicated at 95. This arm has a hollow block 96 forming a pocket 97 provided on its end 65 in a manner such that the opening or pocket large enough to hold one ball therein is normally situated opposite the opening 92 in the partition. It will be seen, therefore, that when the lever member 93 is in the normal position shown in full lines 70 in Fig. 7 and in Fig. 5, the balls or playing pieces drop into the opening or pocket 97 and when a new ball is to be delivered to the field of play the lever member 93 is lifted through the medium of a hook 98 mounted in a shaft 99, the latter hav- 75

ing a handle 100 provided thereon. This lever is thus lifted to the dot and dash line position shown in Fig. 7 where the pocket is brought into opposed relation with an opening 101 through which the ball or playing piece drops on to the field of play. In order to prevent the possibility of the ball dropping back out of the opening due to the knob being positioned adjacent the opening or for any other reason, I provide a gate 102 which is pivoted to the partition 64, as indicated at 103, such gate being adapted to drop down over the opening and rest on a stop 104 when in normal position. In order to prevent the balls or playing pieces remaining in the groove from rolling out of the opening 92 when one of them is being delivered to the field of play, I provide a spring member indicated at 105 which has its end arranged so as to be positioned in the opening 92 when the arm or lever member 93 is raised. The spring stop 95 is secured to the plate 45 as indicated at 106, and is of a resiliency such that it is forced down as indicated in Fig. 5 by the weight of the hollow block or pocket member 96 on the end of the arm or lever.

25 It will be apparent from the foregoing description that the device contemplated by this invention comprises a game apparatus which is of simple form and construction and readily lends itself to use either in a commercial way or as a game for use in the home. As pointed out above, the game is not necessarily confined to the specific construction shown in the drawings, but may be modified by varying the size of the field, the arrangement of the pockets, depressions and paths thereon, and although I consider the particular form of arm and arm operating mechanism to be a novel and important feature to the present invention, I feel that this construction can be modified and varied within wide limits without departing from the actual scope of the invention as set forth in the appended claims.

I claim as my invention:

1. A game apparatus embodying: a case; a field of play mounted in said case, said field of play having a plurality of wells adapted to receive playing pieces; a lever member mounted in said case for swinging and sliding movement in a substantially horizontal plane; a handle on said lever member; an arm pivotally attached to said lever member; and having its end portion positioned above said field of play for moving a playing piece thereover; and a movable fulcrum for said arm.
2. A game apparatus embodying: a case; a field of play mounted in said case, said field of play

having a plurality of wells adapted to receive playing pieces; a lever member mounted in said case for swinging and sliding movement in a substantially horizontal plane; a handle on said lever member; an arm pivotally attached to said lever member; a movable fulcrum for said arm; and yieldable means for holding said arm in a predetermined neutral position.

3. A game apparatus embodying: a case; a field of play mounted in said case, said field of play having a plurality of wells adapted to receive playing pieces; a lever member mounted in said case for swinging and sliding movement in a substantially horizontal plane; a handle on said lever member; an arm pivotally attached to said lever member; and having its end portion positioned above said field of play for moving a playing piece thereover; and a swinging link mounted in said case with its free end pivotally attached to said arm.

4. A game apparatus embodying: a case; a field of play mounted in said case, said field of play having a plurality of wells adapted to receive playing pieces; a lever member mounted in said case for swinging and sliding movement in a substantially horizontal plane; a handle on said lever member; an arm pivotally attached to said lever; a knob on the end of said arm adapted to engage playing pieces on said field of play; and a movable fulcrum for said arm.

5. A game apparatus embodying: a case; a field of play mounted in said case, said field of play having a plurality of wells adapted to receive playing pieces; a lever member mounted in said case for swinging and sliding movement in a substantially horizontal plane; a handle on said lever member; an arm pivotally attached to said lever; a downwardly projecting finger on the end of said arm adapted to engage a playing piece on said field of play; and a movable fulcrum for said arm.

6. A game apparatus embodying: a case; a field of play in said case, said field of play having a plurality of wells therein adapted to receive playing pieces; a universally movable manually actuated jointed member mounted in said case movable over the field of play throughout the said field for moving a playing piece thereon; means for delivering a playing piece to said field of play; releasable means for holding said playing pieces in said wells; and coin controlled means for releasing said playing piece holding means.

WILLIAM R. McDONALD.
